RULING GUIDE

James W. Wilt, Taft, Calif.

Application May 5, 1945, Serial No. 592,239

4 Claims. (Cl. 33—75)

1
The present invention relates to a ruling guide for draftsmen, and has for its principal object the provision of a two part device having a frame which can be held in fixed position and a movable guide member therein which can be shifted both angularly and linearly.

Another object is to provide a ruling guide in which the guide member is held spaced above the surface of the work, in order to prevent smearing, so that the draftsman can make successive lines in ink without waiting for each to dry. Another object is to provide a two part device in which the guide member can be quickly removed from the frame and another substituted, with a different conformation of its ruling edge.

Other objects and advantages of the invention will be apparent from the following description of a preferred form thereof, which should be read with the understanding that the form, construction and arrangement of the several parts may be changed, within the limits of the claims hereto appended, without departing from the spirit of the invention as defined therein.

Reference will be made to the accompanying drawing, in which

Fig. 1 is a plan view of a preferred form of my ruling guide.

Fig. 2 is an end elevation as viewed from the left hand end of Fig. 1.

Fig. 3 is a section on the line 3—3 of Fig. 1.

Fig. 4 is an end elevation as viewed from the right hand end of Fig. 1.

In the drawing, the reference numeral 5 designates an open rectangular frame made of metal, wood, or plastic material, with a flat lower surface. The side members 6 of said frame are formed with inwardly facing grooves 7 which constitute guides for holding a movable flat disk 8. The disk is provided with a slot 9 whose edges 10 form the ruling guides for a pen indicated at 11 in Fig. 3.

The edges 10 of the slot 9 may have any desired contour, either straight and parallel as shown, or curved, and are beveled inwardly toward the bottom to provide a sharp ruling edge. It is contemplated that a plurality of disks will be provided with each frame, each disk having a slot of different contour, so that the user, by substituting one disk for another in the frame, can choose the guide contour best suited to his immediate work.

The disk is movable in the frame, both linearly therein and rotatively, as indicated by the full and broken line positions in Fig. 1. It is also removable, for the substitution of another disk of different slot form, by sliding it out from the end of the frame. To prevent the disk from drop-

2
ping out accidentally during handling of the instrument, a pin 12 is provided at one end of one of the slots 7, and a latch 13 is provided at the other end, which normally obstructs the slot and retains the disk therein, but which can be swung up out of the way to permit removal of said disk when desired.

In using the instrument, the frame 5 is held flat upon the work on the drafting board, preferably against a T-square, and the disk or guide member 8 is moved in the slots 7 until one of its guide edges 10 assumes the desired position. The line is then drawn by causing the pen to follow said guide edge 10. Successive lines or parts of the same line can be drawn by properly shifting the disk without moving the frame, or in some cases, as in crosshatching, the disk can be held stationary in the frame and the frame moved along or with the T-square. If curves rather than straight lines are to be drawn, a disk having the proper slot form or contour is selected. During the drawing of a line, the disk is held stationary by one finger of the same hand that holds the frame stationary.

It will be appreciated that because the disk can be moved both linearly and rotatively in the frame, one of its guiding edges can be brought into any position within the opening of the frame without moving the latter, and because of the elevation of the bottom of the disk above the surface of the work, successive lines can be drawn without waiting for the ink to dry and without smearing.

I claim:

35 1. A ruling guide comprising a frame adapted to lie upon the surface of the work, said frame being formed from a sheet of rigid material having a flat bottom and having two opposite edges turned upwardly and inwardly to form mutually facing parallel grooves, the bottom of said frame being cut away for the major portion of its area, a disk having diametrically opposite portions of its edge slidably seated in said grooves whereby said disk is rotatably and linearly movable in said frame, and said disk member having an aperture therethrough from top to bottom exposing said work surface.

50 2. A ruling guide comprising two spaced parallel members having mutually facing grooves, spaced transverse members connecting said grooved members to form an open frame adapted to lie upon the surface of the work, a disk having diametrically opposite portions of its edge slidably seated in said grooves whereby said disk is rotatably and linearly movable in said frame,

and said disk member having an aperture therethrough from top to bottom exposing said work surface.

3. A ruling guide comprising two spaced parallel side members having mutually facing grooves, spaced transverse end members connecting said side members to form an open frame adapted to lie upon the surface of the work, a disk having diametrically opposite portions of its edge slidably seated in said grooves whereby said disk is rotatably and linearly movable in said frame, said disk having an aperture therethrough from top to bottom exposing said work surface, and means positioned at the ends of said frame for engagement with said disk to prevent removal thereof from said slots, at least one of said disk engaging means being mounted for movement out of said engagement.

4. A ruling guide comprising two spaced parallel members having mutually facing grooves, spaced transverse members connecting said grooved members to form an open frame adapted to lie upon the surface of the work, a disk having diametrically opposite portions of its edge slidably seated in said grooves whereby said disk is rotatably and linearly movable in said frame,

and said disk member having an aperture therethrough from top to bottom exposing said work surface, one edge of said aperture being beveled to form an acute angle with one surface of said disk to form a ruling guide.
